Cooper, Kerr & Dunham

UNITED STATES PATENT OFFICE

ARTHUR C. EVERHAM, OF KANSAS CITY, MISSOURI, ASSIGNOR TO RAYMOND CONCRETE
PILE COMPANY, OF NEW YORK, N. Y., A CORPORATION OF NEW JERSEY

CONCRETE REVETMENT

Application filed April 25, 1929. Serial No. 357,897.

This invention pertains to concrete revetments of a kind now being used to prevent washing away of river banks under flood conditions. This revetment comprises concrete slabs interconnected by longitudinal and crosswise wires to form an articulated mat. The individual slabs or units are usually about one foot wide, four feet long, and three inches thick, and the mats are usually 10 about 140 feet wide and 250 to 300 feet long. The mats are assembled above water level and then lowered to position over the sides of barges.

15 The principal object of the invention is to provide an improved revetment of such design as to tend to anchor itself in position on the river bed and thus better resist displacement, especially on inclined banks. This object is accomplished by use of an improved 20 slab or unit so shaped and reinforced as to save considerable material, without sacrifice of strength, as compared with slabs previously used. Or, if the same amount of material be used, the slab herewith disclosed will 25 give greatly increased strength without additional cost.

Further and other objects and advantages will be apparent from the accompanying specification and drawings, which by way 30 of illustration show what is now considered the preferred embodiment of the invention.

Fig. 1 is a view of a fragment of an articulated mat.

Fig. 2 is an enlarged plan view of one of 35 the slabs of which the mat is composed, with wires.

Fig. 3 is a perspective view of the lower side of the slab shown in Fig. 2.

Fig. 4 is a longitudinal cross-section of the 40 mat in position on the bank.

Referring to Fig. 1, the mat comprises a plurality of slabs 10, reinforced and tied together by longitudinal wires or cables 12 and by lateral wires or cables 14.

45 Referring to Figs. 2 and 3, it will be seen that the bottom of the slab is cut out to form recesses 16 and to leave ribs 18 lengthwise of the slab and ribs 20 crosswise thereof. Wires 14 are embedded in ribs 18 close to the 50 surface thereof, and wires 12 are embedded

in ribs 20, close to wires 14, as may best be seen in Fig. 4. This location of the wires serves to reinforce the slabs on their lower sides, from which material has been removed, so that no strength is sacrificed due to such removal. It will be noted that the wires serve the double purpose of reinforcing the recessed part of the slab and of interconnecting the slabs to form the articulated mat. If desired, additional reinforcing may be 60 added, as for instance at 22.

Fig. 4 shows how the ribs of the slabs settle into the bed of the river and how the material of the bed enters recesses 16 with the result that the mat is well anchored to the bed and is better adapted to resist movement relatively thereto than plain slabs without ribs and recesses. In addition to the mechanical resistance to movement provided by the shape of the slab, a suction resistance is encountered between the recessed portion of the slab and the soil, which tends to hold them in close relationship. The soil in the recess acts as a plunger and tends to create a vacuum or suction when withdrawn from the recess.

It is to be understood that the invention is not limited to the specific embodiment herein illustrated and described but may be used in other ways without departure from the spirit of the claims.

I claim—

1. A revetment comprising a plurality of slab-like bodies each having depending ribs integral with said body and bounding said body on its sides and ends to form a soil pocket and reinforcing elements embedded in and co-extensive with the ribs on all sides of the pocket, said reinforcing wires extending from the sides and ends and similarly reinforcing other slabs held in spaced relation by said wires to form an articulated mat.

2. A revetment comprising a plurality of slab-like bodies, each having depending ribs integral with said body and bounding said body on its sides and ends to form a soil pocket, a partition rib connecting the ribs on the side of the body to divide the pocket into two parts, and reinforcing elements embedded in and co-extensive with the ribs on all sides of the pockets, said reinforcing wires

extending from the sides and ends and similarly reinforcing other slabs held in spaced relation by said wires to form an articulated mat.

3. An article of manufacture comprising a revetment slab having a lower surface partly cut away whereby recesses surrounded by longitudinal and cross ribs are provided, said cross ribs having reinforcing wires embedded therein, and said longitudinal ribs having reinforcing wires embedded therein and co-extensive therewith on opposite sides of the cross ribs and between said cross wires and the upper and lower surface of said ribs said reinforcing wires extending from the sides and ends of said slab and entering and reinforcing similar slabs held in spaced relation by said wires to form an articulated mat.

In testimony whereof I hereto affix my signature.

ARTHUR C. EVERHAM.
